UNITED STATES PATENT OFFICE.

BERNARD ENGLE, OF NEW YORK, N. Y.

ADJUSTABLE FORM.

1,280,429.

Specification of Letters Patent.

Patented Oct. 1, 1918.

Application filed September 1, 1917. Serial No. 189,254.

To all whom it may concern:

Be it known that I, BERNARD ENGLE, a citizen of the United States, residing in the borough of Manhattan, city, county, and 5 State of New York, have invented an Improvement in Adjustable Forms, of which the following is the specification.

This invention relates to an adjustable form adapted to be used by dressmakers in 10 fitting garments, and the object thereof is the provision of a form in which many of the difficulties heretofore experienced in the work of fitting, are overcome. I am aware that heretofore adjustable forms of one type 15 and another have been employed in fitting garments, but my present invention relates more particularly to the construction of an improved adjustable form wherein the parts may be clamped in position to indicate the 20 measurements necessarily used in fitting and after these are once obtained and noted, the form may be set up independently of the body to be fitted, and thus used in fitting the garment in the absence of the person by 25 whom the garment is to be worn.

In carrying out my invention I employ a plurality of tapes made of suitably resilient material secured to one another and connected so as to be adjustable to various positions to enable the user to set up the form both on the body to be fitted and independently thereof. The form is preferably made 30 in halves, adapted to be secured to each other in use so as to be placed on the body to be 35 fitted and removed therefrom, and the construction of my improved adjustable form will be hereinafter more particularly described.

In the drawing:

40 Figure 1 is a front elevation of my improved adjustable form.

Fig. 2 is a sectional elevation taken longitudinally of the form.

Fig. 3 is an enlarged plan of a portion of 45 one of the tapes.

Fig. 4 is a section on line 4—4 Fig. 3.

Fig. 5 is an enlarged section on line 5—5 Fig. 1.

Fig. 6 is an enlarged plan of one of the 50 tapes showing the clamp by which the mem-

bers forming the tape are connected and the scale by which the measurement is indicated.

Fig. 7 is an enlarged section on line 6—6 Fig. 1, and

Fig. 8 is an enlarged section on line 7—7 55 Fig. 1.

Referring to the drawing, my improved adjustable form preferably comprises a plurality of adjustable tapes made of thin steel or other equally resilient material. These 60 tapes are suitably connected and made to extend both longitudinally and circumferentially of the body to be fitted. The form as hereinbefore stated is made in halves. Each half comprises a front longitudinal tape 10 65 and a rear longitudinal tape 11. The upper ends of the tapes 10 and 11 are suitably connected to the opposite ends of the collar tapes 12 while the opposite or lower ends of these tapes 10 and 11 are suitably connected 70 to a hip tape 13. Shoulder tapes 14 are connected at one end to the collar tapes and at the opposite end to arm tapes 15.

I also employ a plurality of circumferential tapes comprising a chest tape 16 and a 75 corresponding back tape connected at their respective ends to the front and back tapes 10 and 11 and the corresponding arm tape 15. There are also bust tapes 17 and 18 connected at their opposite ends to the corresponding front and back tapes 10 and 11 and a waist tape 19, an auxiliary waist tape 20, as well as auxiliary hip tapes 21 and 22 all of which are connected at their respective 80 ends to the front and back tapes 10 and 11. As clearly indicated in Fig. 2, these circumferential tapes pass through and are adjustable in guide loops indicated at 23 suitably 85 connected to the various longitudinal tapes, all of which latter are preferably connected 90 at their lower ends to the hip tape 13 while some of these longitudinal tapes are connected to the collar tapes and others to the shoulder tapes at their upper ends.

Each of these tapes comprises an inner 95 band 24, an outer band 25, and an intermediate band 26 which latter is longitudinally and preferably centrally provided with a slot 26'. The intermediate band 26 is secured at one end to its inner band 24 by 100

rivets or otherwise, and at its other end is free to slide upon the outer surface of its inner band 24, the intermediate band being formed so as to act as a spring in the adjustment of the parts of the band to position. The lower end of the outer band 25 overlies the corresponding intermediate band and adjacent its extremity is provided with a T 27 which is suitably connected thereto and which extends through and is movable in the slot 26' in the intermediate band. This structure is clearly shown in Fig. 8, and by reference to Fig. 4 it will be seen that in order to insure an even movement of the parts; that is to keep the parts in position while being adjusted, the outer band 25 may also be provided with a clamp having overturned ends 28 extending over the adjacent edges of the intermediate band 26.

20 At its upper end each inner band 24 is provided with brackets 29 in which there is pivotally mounted a clamp 30 adapted to be turned down so as to grip the outer band between the tongue of the clamp and the adjacent portion of the inner band, and on each outer band adjacent the clamp 30 there is a scale indicated at 31, it being understood that when the parts are in the position in which they cause the form to assume its smallest shape, the scale will indicate a minimum dimension on each band and upon the band being adjusted to the fitted position and secured in place by the clamp 30 the edge of the clamp will indicate on the scale the dimension of the body corresponding to the tape, it being further understood that the tapes may be designated from each other in any suitable manner so that the dimensions of each tape may be recorded and retained after a fitting is made. As hereinbefore described the longitudinal tapes have been referred to in detail, it being understood however, that the said circumferential tapes are made and adjusted in a similar manner.

25 In suitable positions the front and back longitudinal tapes 10 and 11 may be provided with suitable clamps by which the parts of the form may be secured together.

30 As shown in Fig. 7 a clasp is illustrated comprising a socket 32 suitably secured to the right hand front longitudinal member 10 and a spring clip 33 secured in a similar position to the left hand front longitudinal member 10 and adapted to enter and engage the socket 32 so as to secure the halves of the form together, any suitable number of these clamps being employed to adequately connect the halves of the form and

35 secure the same in position at the rear as well as at the front.

40 From the foregoing it will be apparent that in adjusting the form on the figure to be fitted the clamps 30 are all loosened and

the tapes extended and then drawn back to 65 position and secured in place. It is also to be noted that in adjusting the collar tapes 12 the shoulder tapes 14 will be moved apart to give the proper and corresponding measurements across the shoulders and that in 70 adjusting the arm tapes 15 the longitudinal and circumferential tapes connected thereto will also be shifted correspondingly to allow for the corresponding increase in the measurements indicated thereby. From 75 Figs. 1 and 2 it will be observed that in order to maintain the inner and outer bands of each tape in position relatively to one another I may employ suitably placed bands 80 34 extending around these parts.

I claim as my invention:

1. An adjustable form comprising a plurality of resilient tapes each consisting of an inner band, an outer band, an intermediate band, means for connecting one end 85 of the inner band to the outer band, and devices for connecting the other end of the outer band to slide in the intermediate band.

2. An adjustable form comprising a plurality of resilient tapes each consisting of 90 an inner band, an outer band, an intermediate band having a slot therein, a T secured to one end of the outer band and passing through and slidale in the slot in the intermediate band, and devices for securing the opposite end of the inner band to the outer band and indicating a measurement thereon.

3. An adjustable form comprising a plurality of resilient tapes each consisting of 100 an inner band, an outer band, an intermediate band having a slot therein, a T secured to one end of the outer band and passing through and slidale in the slot in the intermediate band, and a clamp at the opposite 105 end of the inner band adapted to engage the adjacent portion of the outer band and to indicate a measurement thereon provided on this portion on the outer band.

4. An adjustable form comprising longitudinal tapes, a neck tape, arm tapes, shoulder tapes extending between and connected to the neck and arm tapes, the said front and back longitudinal tapes being connected at their upper ends to the said neck and 115 shoulder tapes, a plurality of transverse tapes adjustable circumferentially in predetermined longitudinal tapes, each tape including an inner band, an outer band, an intermediate band, means for connecting 120 one end of the inner band to the outer band, and devices for connecting the other end of the outer band to slide in the intermediate band.

5. An adjustable form comprising longitudinal tapes, a neck tape, arm tapes, shoulder tapes extending between and connected to the neck and arm tapes, the said front

and back longitudinal tapes being connected at their upper ends to the said neck and shoulder tapes, a plurality of transverse tapes adjustable circumferentially in pre-
5 determined longitudinal tapes, each tape including an inner band, an outer band, an intermediate band, means for adjustably se-

curing one end of the inner band to the outer band and simultaneously indicating a measurement thereon, and devices for connecting the opposite end of the outer band to slide in the intermediate band. 10

Signed by me this 30 day of August 1917.
BERNARD ENGLE.
